UNITED STATES PATENT OFFICE.

OTIS A. MYGATT, OF NEW YORK, N. Y.

PRESSED OR MOLDED GLASSWARE.

1,101,035.

Specification of Letters Patent. Patented June 23, 1914.

Application filed June 23, 1908. Serial No. 439,988.

To all whom it may concern:

Be it known that I, OTIS A. MYGATT, a citizen of the United States, residing at New York, in the county of New York and State 5 of New York, have invented certain new and useful Improvements in Pressed or Molded Glassware, of which the following is a specification, reference being had thereto in the accompanying drawings.

10 The object of my invention is to make glassware, such as tableware, flower vases and glass inclosures for artificial light, etc., more brilliant and attractive.

A glass inclosure having on its outer surface 15 designs formed of ribbings running in two or more directions is provided with interior radial prisms to enhance the brilliancy of the outer decorative design. Interior longitudinal flutings for purposes of 20 light diffusion have been used in connection with horizontal light distributing prisms, but this type of fluting would not, even if used with outside decorative designs, increase their brilliancy.

25 Figure 1 is a bottom perspective of an inclosure embodying my invention. Fig. 2 is a bottom perspective of another inclosure embodying my invention. Fig. 3 is a bottom perspective of another inclosure embodying 30 my invention. Fig. 4 is a horizontal cross-section of Fig. 3 on lines 4—4 except that the section is shown as straight for the purpose of indicating the path of light rays more simply.

35 The designs on the outside of the glassware shown in the figures are composed of ribbings which run in two or more directions, that is, there are always a certain number of outer corrugations which do not 40 parallel the inner corrugations. Longitudinal double reflecting prisms are employed on the inside of the inclosures to provide a backing for the exterior designs. In this manner a portion of the light rays entering

45 through the corrugations on the outside of the inclosure is reflected back by the interior double reflecting prisms, thus causing the exterior designs to appear more brilliant than they would with a smooth interior surface. 50 The operation is shown in Fig. 4 which is a cross-section in which the double reflecting prisms X are on the inner surface and transmitting ribs running in two or more directions are on the outer surface Y.

This is the combination which would be employed in an inclosure to be viewed by daylight, that is, the exterior ribbings are not to be used to reflect light down and out of the open mouth of the inclosure, but to allow transmission. To the left of the diagram 55 is shown the direction of the light rays a, a', a'', etc., entering and emerging at various points, and to the right the spreading and converging of the light emitted by small sections b, b' of the surface. The parallel incident rays converge and spread causing high and low light areas to appear on the outer surface of the glass. This is caused by the inner longitudinal reflecting prisms.

In inclosures which are intended to transmit light from sources within (not to reflect it down), or to receive light from outside the inclosure as in the case of globes or tableware I employ designs on the outside which are composed of refracting light transmitting ribs running in a plurality of directions in combination with the interior double reflecting radial prisms above referred to. Fig. 4 shows the passage of light rays in that event.

Where the inclosure is intended as an artificial light reflector, I use designs embodying double reflecting prisms on the outside of the glass, in combination with inner radial double reflecting prisms.

85 In most cases it is possible to employ the same molds which are now used for making the various types of decorative pressed glassware by making new plungers for the same. Instead of the usual smooth plunger 90 substitute a plunger of exactly the same shape, but having substantially longitudinal ribs of angular outline cut upon it.

The expression "longitudinal prisms or corrugations" has been employed, but the term is intended to include all prisms or corrugations which lie in planes common to the axis of the glass inclosure.

Having described my invention, what I claim is:

100 1. Glass inclosures having on their outer surface corrugations running in a plurality of directions, and on their inner surfaces substantially double reflecting prisms lying in planes passing through the axis of the glass inclosure.

105 2. Glass inclosures having decorative designs carried out in corrugations on their

outer surface, and their inner surface covered with substantially double reflecting prisms lying in planes passing through the axis of the glass inclosure.

- 5 3. Glass inclosures having on their outer surface curved outline corrugations banded by lines running in more than two different

directions, and on their inner surface substantially longitudinal reflecting prisms.

OTIS A. MYGATT.
